UNITED STATES PATENT OFFICE.

CHARLES H. CURRAN, OF HOLYOKE, MASSACHUSETTS, ASSIGNOR OF ONE-HALF TO JAMES J. CURRAN, OF SAME PLACE.

INHALER.

SPECIFICATION forming part of Letters Patent No. 631,621, dated August 22, 1899.

Application filed November 16, 1898. Serial No. 696,582. (No model.)

To all whom it may concern:

Be it known that I, CHARLES H. CURRAN, a citizen of the United States of America, residing at Holyoke, in the county of Hampden and State of Massachusetts, have invented new and useful Improvements in Instruments for Administering Medicinal Preparations by Inhalation, of which the following is a specification.

10 This invention relates to instruments for administering medicinal preparations to the nasal organs by inhalation, the object being to provide an "inhaler," so called, of improved construction for applying a dry powder or liquid remedy, as above stated; and the invention consists in the peculiar construction of the device as to the details thereof, and particularly to means contained therein, whereby the person using the same can graduate the quantity of the medicament or remedy inhaled while holding the device to the nose, all as hereinafter described, and more particularly pointed out in the claim.

In the drawings forming part of this specification, Figure 1 is a longitudinal section of an inhaler embodying my invention, the same illustrating the position thereon of the thumb or finger of the operator while using the same and showing the cover removed. Fig. 2 is a 25 longitudinal section of the exterior case of the instrument and a side view of the inner movable tube thereof. Fig. 3 is a perspective view illustrating the position of the inhaler in the hand during the use thereof and 30 showing the outline of a part of the nose and the nostril of the user to which the end of the inhaler is applied.

Referring to the drawings, 2 indicates the case of the inhaler, which is preferably of 35 metal and of cylindrical tubular form, with the bottom end closed and having a concentric bead 5, projecting from the surface of said case 2 near its open end. Between said concentric bead and said open end of the case 45 is an air-inlet 6, which is adapted to have the area of its opening varied while being used, as below set forth, whereby the quantity of the remedy that shall be discharged from the instrument is regulated.

50 3 indicates the inner movable tube of the instrument, which has its outer end *e* suitably formed and provided with an outlet 10

of cone shape or tapering form to be applied to the nostril of the user, as shown in Fig. 3, wherein B indicates the outline of the nose, 55 and *c* of a nostril. Said inner tube has a longitudinal air-conducting groove 7 in the side thereof, extending from near its inner or larger open end to a point near its upper end a little beyond said air-inlet in the said case, 60 with which groove said air-inlet 6 is normally in communication, and has an air-passage 9 formed in its lower end at the point where said groove 7 terminates. The normal operative position of said inner tube in said case 6; is with its lower end abutting against the inner side of the bottom of said case, so that the sole air communication between said air-conducting groove 7 and the interior of said inner tube 3 is through said air-passage 9, 70 and this being close to the bottom of said case the air passing therethrough must act under the remedy and cause the upheaval or volatilization thereof with the best results as to charging the air therewith. Just above the 75 upper end of said air-conducting groove 7 in the inner tube 3 is formed a depression 8 for engaging the finger or thumb therein to aid in withdrawing said tube from said case for placing a medicinal substance in the 80 latter. A cap or cover 4 is provided to be placed over the said outer end *e* of the inner tube 3 and over the upper end of said case 2, which when so placed abuts against said concentric bead 5, and thus effectually covers and protects said parts.

While the within-described instrument is mainly designed to be used for administering a dry-powder remedy, (indicated by *d* in Fig. 1,) it is obvious that many liquid remedies 90 may be successfully applied by its use, and especially those which are of a volatile nature.

In using the instrument with either a dry-powder or a liquid remedy the said air-passage 9 (in the lower end of the said tube 3) occupies the same position, which is one close to the bottom of the case 2 and under the body of the remedy therein, as indicated by *d* in Fig. 1, as aforesaid.

The instrument is held for use substantially 100 in the manner indicated in Fig. 3, whereby the thumb or finger of the patient or operator serves as a valve to open the air-inlet 6 more or less, thereby effecting a greater or less dis-

charge of the remedy contained in the instrument through the open end thereof into the nostril of the patient, occasioned by the inhalation by the latter of air into the nostril, which is drawn through said inlet and the instrument and takes up on its way the remedy placed in the latter to a greater or less extent, as desired by the operator.

Having thus described my invention, what I claim, and desire to secure by Letters Patent of the United States, is—

An instrument for administering medicinal preparations through the nasal organs, by inhalation, combining a tubular case open at one end for receiving a medicinal substance, having an opening through the side thereof for the admission of air thereto, the superficial area of which may be varied by placing the thumb or finger of the user more or less

thereover, combined with a second tubular case fitted to slide within said first-named case having an open outer end, through which said substance is inhaled, and a longitudinal groove in the side thereof extending, operatively, from near the lower end thereof to a point opposite, and communicating with, said air-admitting opening whereby air entering therethrough may pass downwardly through said groove and circulate in the base of said outer case, and take up said medicinal substance, and with the same pass out through the open end of said inner case, substantially as described.

CHARLES H. CURRAN.
